JOSEPH H. STRAUS, JR., OF BALTIMORE, MARYLAND, ASSIGNOR OF ONE-HALF TO
RAYMOND H. WILLIAMS, OF BALTIMORE, MARYLAND.

WIRE CLIP FOR CONCRETE CONSTRUCTION.

1,025,330.

Specification of Letters Patent.

Patented May 7, 1912.

Application filed February 26, 1912. Serial No. 679,909.

To all whom it may concern:

Be it known that I, JOSEPH H. STRAUS, Jr., a citizen of the United States, residing at Baltimore city, State of Maryland, have invented certain new and useful Improvements in Wire Clips for Concrete Construction, of which the following is a specification.

This invention relates to means for securing reinforcing bars in position in molds for concrete work so as to prevent their displacement (and the consequent injury or ruin of the finished work) while the concrete is being poured or otherwise manipulated previous to setting or hardening.

The general object of the invention is to provide improved means for this purpose especially adapted to the securing together of reinforcing bars which cross each other at right or other angles.

A further object is to provide such securing means of such a character that the concrete worker may make them himself at the work, to suit general or particular forms.

25 A further object is to provide securing means with improved means for supporting the secured together bars at a suitable height from the bottom of the mold.

With these and other objects in view, the invention consists in a clip or clamp of the improved form, and of the material herein-after fully described and afterward specifically claimed.

In the accompanying drawings, which illustrate preferred embodiments of the invention, Figure 1 represents, in perspective view, my improved clip as applied to a pair of reinforcing bars, crossing each other at substantially a right angle. Fig. 2 represents in perspective detail the clip before it is applied to the reinforcing bars. Fig. 3 represents a sectional view on a plane cutting through a concrete structure alongside of one of two crossed reinforcing bars, showing the other bar in section, with my improved clip being shown applied to the cross bars, in elevation. Fig. 4 represents a view in elevation of the clip in the form of Fig. 2 applied to the two crossed reinforcing bars, prior to making the bend in the clip which locks it in position on the bars. Fig. 5 represents a view similar to Fig. 1 of a modified form of clip. Fig. 6 represents the modified form of clip of Fig. 5 in perspective, unapplied to reinforcing bars. Fig. 7 represents

a view in side elevation, of two crossed reinforcing bars, with my improved clip applied thereto. Fig. 8 represents, in similar view, the parts shown in Fig. 7, looking at the opposite side.

Like reference characters mark the same parts wherever they occur in the various figures of the drawings.

Referring specifically to Figs. 1 to 4, inclusive, of the drawings A and B indicate reinforcing bars which lie horizontally and cross each other in contact and which are especially intended in this position as reinforcements for horizontal concrete constructions, such as floors, and the like, as at C. In Fig. 2 my improved clamp is shown in the form in which it appears before applying it to the crossed bars A and B, each end of the wire being bent to form vertical legs or supports, as at 1 and 2, the former appearing in this figure in the position it assumes when the clip is applied to the bars and the latter inverted, from which inverted position it is reversed during the process of applying the clip to the bars as herein-after explained. Each of these legs or supports 1 and 2 is formed by bending the wire at its opposite ends into parallel stretches, as at 3 and 4, and 5 and 6, respectively and at the inner extremity of the parallel stretches, as at 7 and 8, the wire is bent into curves, as at 9 and 10, the curve 9 being reversed in position from the curve 10. In the preparatory form shown in Fig. 2, the outer ends of the two curves 9 and 10 are connected by a long, nearly straight stretch 11, the connection of this stretch with curve 9 being in the form of a reversed curve 12, and with curve 10 in the form of an angle, at 13. The clip constructed as described, and as illustrated in Figs. 2 and 4, is applied to the crossed bars A and B by passing the curve 9 under the bar B and the reverse curve 10 over the bar A, as shown in Fig. 4, in which position the long connecting stretch 11 passes under the bar B. To lock the clip in position, the wire of the stretch 11 is bent into a loop 14, around the bar B, that part of the stretch 11 not used in the loop extending along the bar A, and the leg or support 2 being reversed from the inverted position of Figs. 2 and 4 to the upright position of Figs. 1 and 3, with the loop 10 extending under and forming a rest or support for the bar A, the legs 1 and 2

resting upon the bottom of the mold in which the concrete, as at 15, Fig. 3, is shaped, and the bars A and B being clamped together and supported in the loops 10 and 9.

In the modified form of clip illustrated in Figs. 5 to 8, inclusive, the clip is of the same form as hereinbefore described and shown in Figs. 2 and 4, inclusive, except that the leg or support 2 is omitted, and owing to this omission the manner of applying the clip to the crossed bars A and B is slightly modified. In such application, the stretch 11 is not bent under and around the bar B, forming the loop 14 but the curve 10 is simply engaged over the top of the bar A, with the result that the bar B is supported in the loop curve 9 and the bar A held in contact with bar B by the loop 12, as in the construction of Figs. 1, 3 and 4, the latter function being assisted, and the clip held in position, by the engagement of the curve 10 over the top of bar A.

Having thus fully described my invention, what I claim as new and desire to secure by Letters Patent of the United States is—

1. A wire clip for securing together crossing bars for concrete reinforcement comprising an upright leg or support at one end, an adjacent downward curve for engaging under one of the bars, bends in the wire extending in position to pass over the second bar and under the first bar, and a support at the other end of the wire.

2. A wire clip for securing together crossing bars for concrete reinforcement comprising an upright leg or support at one end, an adjacent downward curve for engaging under one of the bars, bends in the wire extending in position to pass over the second bar and under the first bar and a support at the other end of the wire, said sup-

port being inverted in position with relation to the first mentioned support.

3. A wire clip for securing together crossing bars for concrete reinforcement comprising an upright leg or support at one end, an adjacent downward curve for engaging under one of the bars, bends in the wire extending in position to pass over the second bar and under the first bar, and a curve and a second support at the other end of the wire.

4. A wire clip for securing together crossing bars for concrete reinforcement comprising an upright leg or support at one end, an adjacent downward curve for engaging under one of the bars, bends in the wire extending in position to pass over the second bar and under the first bar, and a curve and a second support at the other end of the wire, said curve and support being reversed with relation to the first mentioned curve and support.

5. A clip for securing together crossing bars for concrete reinforcement made of a single piece of stiff flexible wire, said wire having two parallel stretches at one end forming a vertical leg or support, a downward curve beginning at the upper end of the leg, a loop formed of a continuation of the wire from the end of said curve, a long substantially horizontal stretch beginning at the termination of said loop, an upward curve at the termination of said long stretch, and two parallel vertical stretches beginning at the termination of the last named curve forming an inverted leg or support.

In testimony whereof I affix my signature in presence of two witnesses.

JOSEPH H. STRAUS, JR.
